UNITED STATES PATENT OFFICE

JOHN C. MILLER, JR., OF CHICAGO, ILLINOIS, ASSIGNOR, BY MESNE ASSIGNMENTS, TO THE LAKE ERIE CHEMICAL COMPANY, OF CLEVELAND, OHIO, A CORPORATION OF OHIO

VAULT-PROTECTIVE DEVICE

Application filed August 30, 1928. Serial No. 302,961.

This invention relates to vault protective devices and has special reference to the installation of noxious gas bombs in connection with large vault doors of the banking and safety deposit types where the vault is subject to a steady traffic during the time it is open.

Heretofore, vault protective devices of the general type indicated have been applied to ordinary vault doors with some success but in attempting to incorporate such gas protective devices in connection with modern bank vaults, it has been found undesirable and impractical to mount the gas bomb and its operating mechanism in an exposed position on the door due to the large number of people passing in and out and the consequently increased risk of the mechanism being tampered with. I have found it to be desirable to mount the gas bomb independently of the door, as in a screened recess in the vault vestibule or the vault itself, and to provide means for connecting the operating mechanism on the door to the gas bombs when the door is closed.

It is accordingly an object of this invention to provide an actuating mechanism adapted to automatically transmit an actuating impulse from the door to the bomb when the latter is mounted independently of the door, and to so form the said mechanism that it will be automatically disconnected upon opening the door, thus avoiding any risk of an operation of the bomb during the normal use of the vault.

It is another object of this invention to provide an improved and more sensitive bomb releasing mechanism that will reduce the lag and friction in said mechanism when an attempt is made to effect an unauthorized or forcible entry thru the door.

Other and further important objects of this invention will be apparent from the disclosures in the specification and accompanying drawings.

The invention (in a preferred form) is illustrated on the drawings and hereinafter more fully described.

On the drawings:

Figure 1 is a perspective view of a large vault door having the installation of this invention diagrammatically indicated in connection therewith.

Figure 2 is a diagrammatic layout of the wiring system acting to restrain the operation of the gas bombs.

Figure 3 is an enlarged detail of the connection between the wiring system of Figure 2 and the bomb releasing lanyard.

Figure 4 is a vertical section of one gas bomb.

Figure 5 is a fragmentary section of the plunger releasing mechanism of Figure 4 in released position.

Figure 6 is a detail section on the line VI—VI of Figure 4.

Figure 7 is a detail section on the line VII—VII of Figure 4.

Figure 8 is a section of that part of the actuating mechanism incorporated in the door.

Figure 9 is a fragmentary section of the entire actuating mechanism.

Figure 10 is a plan view of the bracket to be mounted in the vault vestibule.

Figure 11 is a face view of the bracket of Figure 10 with the cover removed.

As shown on the drawings:

The vault door construction chosen to illustrate the application of this invention is one such as is commonly used in modern bank vaults and comprises a vestibule 10 receiving a thick door 11 having stepped edges 12 with a series of locking bolts 13 mounted in a skeleton framework 14 which is usually covered with a glass plate. Combination and time locks 15 are mounted on the inner face of the door in the center of the framework 14.

A pair of gas bombs, indicated generally by the numeral 16, are mounted in any desired manner either within the vault proper or in the vestibule 10. Two bombs have been shown because the usual vaults of the type under consideration are of such a large volume that a single bomb might not have sufficient capacity to rapidly fill the vault with noxious gas.

The bomb proper, chosen for illustrating the installation of this invention, comprises a slotted shield 17 surrounding a sealed nox-

ious gas container 18 having an apertured cover 19, the apertures in which are sealed by an impervious frangible material 20 such, for example, as waxed paper. The shield 17 is secured on a centrally apertured neck 21 which is formed to receive a plurality of blank rim fire cartridges or caps 22.

A firing pin 23 is slidably mounted in a guide 24 attached to the neck 21 in a position to simultaneously engage each of said cartridges. The firing pin 23 is coaxial with a guide tube 25 of a hardened material adapted to be drill proof, this tube containing a plunger 26 backed by a spring 27. The upper end or stem 28 of the plunger 26 is formed with a groove engageable by balls 29 carried by an enveloping member 30 which slides in a tube like cap 31 small enough, except at the bottom, to hold the balls in the stem groove. When the member 30 is released, it, together with the plunger 19, moves downwardly in the tube 25 until the balls reach the enlarged lower end thereof when they are free to disengage from the plunger 26 which then completes its travel to strike the firing pin as shown in Figure 5. The member 30 is normally held up in the position shown in Figure 4 by a Bowden wire 32 within a flexible enveloping sheath 33. This sheath is preferably of a hardened character adapted to resist pinching and to break if crushed, in order to release the wire. This Bowden wire combination forms a flexible lanyard which permits a wide choice of independent locations for the bombs and the holding mechanism for the other or free end 34 of the Bowden wire.

A safety locking pin 35 or shut off is mounted in clamp 36 secured to the guide tube 25 of the first bomb in such a position that when the pin 35 is screwed in, by means of the threaded enlargement 37 thereof and the knurled head 38, it acts to prevent full travel of the plunger 26. The pin 35 is provided with a frangible sealed wire 39 to prevent its unauthorized use, the rotation of the pin severing the sealing wire the lower portion of which then drops out, forming a visual indicator of the condition of the safety device.

As shown in Figure 4, the firing pin 23 is arranged with a traverse aperture 40 through which is passed the free end 34a of the Bowden wire for the second bomb, the end of the wire being then fastened in the pin guide 24. The pin 23 thus acts as a shear to sever and release the Bowden wire for the second bomb when the first bomb is fired, thus placing the second bomb in series with the first to double the gas discharging capacity for large vaults.

The free end 34 of the Bowden wire on the first bomb leads to a bracket 41 mounted in the vestibule 10 in alignment with the edge of the door when the latter is closed. The bracket 41 carries a boss 42 containing a guide

43 for the Bowden wire which passes through a retaining washer 44 and is knotted or otherwise secured as shown in Figure 9, the guide 43 serving as an abutment for the end of the sheath 33 to maintain the same under compression. The guide 43 is formed as a cup like member to act as a shear in conjunction with the washer 44 when the latter is displaced sideways. A sliding plunger 45 is so mounted in the boss 42 at right angles to the axis of the guide 43 as to be in a position to engage the washer to cause the same to shear the Bowden wire passing therethrough. An enlarged head 46 is formed on the plunger and is located in a recess 47 in the boss, the recess being normally covered by a frangible cover 48 retained in position by a frame 49.

The hereinbefore described mechanisms comprise all that part of my invention that is not physically associated with the door. It will be evident from the preceding description that no parts directly associated with the gas releasing mechanism are in operative position relative to the vault door after the latter has been opened, thus preventing accidental discharge of the gas bombs or tampering therewith during the normal day to day use of the vault.

An actuating mechanism adapted to bridge the gap between the door and the bracket 41 is shown in Figure 8 and is very similar in principle to the bomb firing mechanism.

The framework 14 for the door locking bolts 13 is provided with aligned apertures, the aperture 50 in the inner frame 14a being provided to receive a tube like cap 51 duplicating the bomb cap 31. The internal mechanism is practically a duplicate of the bomb mechanism, and the same reference numerals have been applied thereto except for the firing pin 52, which slides in an aperture 53 in the outer frame 14b.

In order to protect the plunger under normal conditions, a frangible diaphragm 54 is secured over the aperture 53 by a ring 55. The firing plunger 26 and spring 27 are in this case mounted in a tube 56 secured to the cap 51 and having another tube 57 engaged in telescopic relationship therewith to enclose the mechanism despite variations in the distance between the frame members 14a and 14b. A Bowden wire 58 and a hardened sheath 59 therefor lead to a holding mechanism shown in Figure 3 which may be placed in any convenient position on the door. The free end 60 of the Bowden wire 58 is secured to the shackle 61 of a movable pulley 62 within a spacer member 63 against the top of which the sheath 59 abuts. This spacer member is made of a hardened drill proof material in order to prevent clamping of the movable releasing mechanism therein. The member 63 carries a fixed pulley 64 near its lower end. The two pulleys just described are normally held in the relative position

shown by a loop 65 in a flexible wire 66 passing around the pulleys.

The wire 66 is trained or passed over a series of fixed pulleys 67 in such a manner as to pass back and forth over the surface of the door. Special loops 68 and bends 69 are formed in this wire over the more vulnerable lock portions of the door, it being understood that the wire 66 is entirely free to move over the pulleys, the ends of the wire being joined together to form an endless loop. By so forming the wire into an endless loop, should the wire be cut under the worst possible conditions, only half the length of the wire would have to be moved relative to the pulley system in order to release the movable pulley 62 and thus operate the actuating mechanism.

In order to further increase the sensitivity or responsiveness of the wiring system by reducing friction therein, a movable pulley 70 is engaged with the wire 66 and the shackle 71 of this pulley is connected by a wire 72 to the shackle of another movable pulley 73 which is similarly included in a second substantially endless wire 74 trained over fixed pulleys 75. With this system, severing any one of the wires 66, 72 or 74 results in a release of tension in all three wires with a consequent operation of the actuating mechanism. The multiple wiring system also has the advantage of preventing the system from being rendered inoperative by an attempt to clamp the wires during an attempt to cut a hole through the door. In order to adjust the initial tension of all three wires, a single turnbuckle 76 in any of them would be sufficient. As shown, this turnbuckle is used to join the ends of the wire 74 in lieu of otherwise securing these ends together.

The operation of the major units has been described in connection with the structures thereof so that a short resumé of the coaction of the different parts will be given.

The wires 66, 72 and 74 are normally maintained under constant tension by the spring 27 in the relay mechanism which maintains the Bowden wire 58 under considerable load. Should any of these wires, including the Bowden wire, be cut or severed in any manner, the spring 27 acts to push down the firing plunger 26 in the relay mechanism, the plunger striking the pin 52 and driving it through the frangible diaphragms on the door frame 14b and bracket 41 and into contact with the plunger 45 which in turn strikes the washer 44 which cuts the bomb releasing Bowden wire 32 releasing the firing plunger in the first bomb which in turn cuts the Bowden wire restraining the operation of the second bomb.

The above described sequence of events occurs in a fraction of a second so that the two bombs will start discharging gas almost simultaneously with a severance of the door wiring system at any point. With large vault

doors of the type under consideration, the only practical system of attack is by means of explosives or a cutting torch. Any torch powerful enough to cut through a foot or more of steel will also obviously sever or melt a small and flexible wire of the type required. 70

It will thus be seen that I have invented a sensitive yet safe noxious gas bomb installation for large vault doors that is automatically disconnected when the vault door is 75 opened in the usual manner.

I am aware that numerous details of construction may be varied through a wide range without departing from the principles of this invention and I therefore do not purpose 80 limiting the patent granted, otherwise than necessitated by the prior art.

I claim as my invention:

1. A vault protective device comprising in combination with a noxious gas bomb and means for bursting the same, an actuating mechanism divided between the door and its frame and adapted to bridge from the vault door to its frame when said door is closed, means operatively connecting the door frame 85 part of said actuating mechanism to said bomb bursting means, and means for releasing the door portion of the actuating mechanism upon injury to the door.

2. A vault protective device comprising in combination with a noxious gas bomb and means for bursting the same, an actuating mechanism divided between the door and its frame and adapted to bridge from the vault door to its frame when said door is closed, 90 means operatively connecting the door frame part of said actuating mechanism to said bomb bursting means, and means for normally restraining the operation of the door portion of said actuating mechanism comprising a plurality of interengaging wires disposed over the vulnerable portions of the vault door.

3. A device of the class described comprising a noxious gas bomb and means for discharging said bomb, an actuating mechanism comprising a restraining mechanism for said means mounted in the door frame of a vault, means mounted on the vault door for releasing said restraining mechanism, and means 110 for actuating the door portion of the actuating mechanism upon injury to the door.

4. A device of the class described comprising a noxious gas bomb and means for discharging said bomb, an actuating mechanism comprising a restraining mechanism for said means mounted in the door frame of a vault, means mounted on the vault door for releasing said restraining mechanism, and means for normally restraining the operation of the 120 door portion of the actuating mechanism.

5. In combination, a vault gas bomb, an operating system therefor comprising a network of movable wires, the injury of which is adapted to operate said bomb, and a separable 130

actuating mechanism comprising cooperating parts interposed between said wires and said bomb, said actuating mechanism parts being so mounted on the vault door and its frame that said parts are separated when the door is open.

In testimony whereof I have hereunto subscribed my name at Chicago, Cook County, Illinois.

JOHN C. MILLER, JR.
